Primary Examiner — Rhea Shields(74) Attorney, Agent, or Firm — Millen, White, Zelano, Branigan, P.C.(57) CLAIM

The ornamental design for a toilet bowl brush, as shown and described.

DESCRIPTION

FIG. 1 is a top perspective view of the toilet bowl brush showing my new design.

FIG. 2 is a front view thereof.

FIG. 3 is a back view thereof.

FIG. 4 is a side view thereof.

FIG. 5 is another side view thereof.

FIG. 6 is a top view thereof; and,

FIG. 7 is a bottom view thereof.

The broken lines in the drawings illustrate portions of the toilet bowl brush which form no part of the claimed design.

1 Claim, 7 Drawing Sheets(56)
